UNITED STATES PATENT OFFICE.

RUDOLPH CONRADER, OF ERIE, PENNSYLVANIA.

APPARATUS FOR ACTUATING LIQUID WITH COMPRESSED GAS.

SPECIFICATION forming part of Letters Patent No. 664,723, dated December 25, 1900.

Application filed August 28, 1899. Serial No. 728,718. (No model.)

To all whom it may concern:

Be it known that I, RUDOLPH CONRADER, a citizen of the United States, residing at Erie, in the county of Erie and State of Pennsylvania, have invented certain new and useful Improvements in Apparatus for Actuating Liquid with Compressed Gas; and I do hereby declare the following to be a full, clear, and exact description of the invention, such as will enable others skilled in the art to which it appertains to make and use the same.

This invention relates to apparatus for actuating liquid with compressed gases; and it consists in certain improvements in the construction thereof, as will be hereinafter fully described, and pointed out in the claims.

A leading object of my invention is to utilize the expansive force of gases to the fullest extent possible in actuating liquids. My apparatus is peculiarly planned with this in view.

In carrying out my invention in its preferred form I utilize a series of pump-chambers, which are ordinarily arranged one above another, the lowest of said chambers being positioned to be filled with the liquid to be actuated. The gas under pressure is utilized to expel the liquid from said chamber to the second of said chambers, and then the gas-supply is cut off from the first chamber and a gas connection is opened between the first and second chambers, whereby the expansive force of gas in the first chamber is utilized to expel the liquid from the second chamber.

The lifts of the chambers when used in the ordinary form, as above described, must be arranged so that the expansive force of the gas in the first chamber will be sufficient to expel the liquid from the second chamber.

Carrying my invention further, a third chamber may be added, into which the liquid is conducted from the second chamber, and the expansive force of the gases in the first and second chambers may be utilized to expel the liquid from the third chamber. Thus the expansive force of the motor or actuating gas may be utilized until the number of lifts possible is attained, being dependent upon the initial pressure of motor-gas. After the expansive force of the initial supply of motor-gas is exhausted a new series of chambers may be added, taking up the liquid from the last of

the first series and subjecting it to a fresh supply of motor-gas. By this arrangement a given lift can be accomplished with a smaller pressure of motor-gas.

Among other features of my invention may be stated generally valve mechanisms arranged to effect the movements of actuating-gas through the local action of the liquids and gases at the chambers, a system of overflowing devices which will permit the complete filling of the system without blocking the movement of any of the other parts of the system, and various details of construction, which will appear more fully in the specification and claims.

The invention is illustrated in the accompanying drawings, as follows:

Figure 1 shows an outline elevation of the apparatus. Fig. 2 shows a detailed view of the actuating-gas valve on the lines 2 2 in Figs. 3, 4, and 5. Fig. 3 is a section on the lines 3 3 in Figs. 2, 4, and 5. Fig. 4 is a section on the lines 4 4 in Figs. 2 and 3. Fig. 5 is a section on the lines 5 5 in Figs. 2 and 3. Fig. 6 is a central section on the lines 6 6 in Fig. 7 through the valve mechanism of the low-pressure chamber. Fig. 7 is a section on the lines 7 7 in Fig. 6. Fig. 8 is a central section on the lines 8 8 in Fig. 9 of the overflow-valve arranged on the low-pressure chamber. Fig. 9 is a plan view of the same. Fig. 10 is a central section on the lines 10 10 of the drain-valve of the last low-pressure chamber in the series. Fig. 11 is a plan view of the same.

A marks the high-pressure chamber of the first series; *a*, the high-pressure chamber of the second series; *A'*, the first low-pressure chamber of the first series, *A²*, the second low-pressure chamber of the first series, and *a'* the first low-pressure chamber of the second series.

B marks the inlet-valve for liquid to the chamber *A*; *B'*, the inlet-valve to the chamber *A'*; *B²*, the inlet-valve to the chamber *A²*; *b*, the inlet-valve to the chamber *a*; *b'*, the inlet-valve for the chamber *a'*, and *C*, *C'*, *C²*, and *c* the connections between the chambers *A*, *A'*, *A²*, *a*, and *a'*, respectively, the said connections running through the inlet-valve just hereinbefore described. An outlet *c'* extends from the chamber *a'*.

- D marks the pipe forming the connection with the gas-supply; d, the pipe forming the connection between the pipe D and the high-pressure chamber a.
- 5 E marks the valve mechanism controlling the flow of gas to and from the high-pressure chamber; E' and E², the valves controlling the flow of gas from the chambers A' and A², the valve e controlling the flow of gas to and 10 from the chambers a and the valves e' controlling the flow of gas from the chambers a'.
- F and F' mark the pipe forming the gas connection between the chambers A and A' and A' and A², respectively.
- 15 F² marks the gas-exhaust pipe from the chamber A², f the pipe forming the gas connection between the chambers a and a', and f' the exhaust-pipe from the chamber a'.
- G', G², and g' mark the overflow-valves, arranged on the low-pressure chambers.
- 20 H' marks the drain-valve for the last of the low-pressure chambers of the first series; h, a pipe forming the connection with the high-pressure chamber a for conveying and actuating fluid to the valve. H' and H² mark the pipe forming the connections between the chamber A² and the valve H' through which the surplus liquid in the chamber A² may be drained.
- 25 30 By reference to Fig. 1 the operation of the device may be generally described as follows: Liquid enters by any means, preferably by gravity, the initial or high pressure chamber A. As soon as this chamber is filled with liquid the liquid operating through the medium of a float (shown in dotted lines) actuates the valve mechanism E to open the connections to the gas-supply through the pipe D and close the connection with the chamber A' through the pipe F. A check-valve in the valve mechanism B prevents the outflow of liquid through the passage by which it enters the chamber A and turns the liquid as it is expelled by the gas supplied through the pipe D into the pipe C, through which it is conveyed into the chamber A'. All the chambers are preferably made of the same size, so that the liquid expelled from the chamber A will exactly fill the chamber A'. As soon as 40 the chamber A becomes emptied the weight of the float actuates the valve mechanism E to close the connection with the pipe D and to open the connection with the pipe F. The check in the valve mechanism B' prevents the return flow of the liquid from the chamber A' to the chamber A. A float (shown in the dotted lines in the chamber A') actuates, when said chamber is filled with liquid, the valve mechanism E' to close the connection 45 with the pipe F'. The expansive force of the gas in the chamber A operating through the pipe F upon the liquid in the chamber A' expels the liquid in the chamber A', through the pipe C', into the chamber A². The action 50 of the float in the chamber A' as soon as said chamber is emptied of liquid operates upon the valve mechanism E' to open the connec-

tion between the chamber A', through the pipe F', with the chamber A². A check-valve in the valve mechanism B² prevents a return flow of the liquid from the chamber A². A float in the chamber A² actuates the valve mechanism E² to close the exhaust through the pipe F². The liquid in the chamber A² is then subjected to the expansive force of the gases contained in the chambers A and A'. This force expels the liquid from the chamber A², through the pipe C², into the chamber a. As soon as liquid has been expelled from the chamber A² the float in said chamber actuates the valve E² to open said chamber to the exhaust F². This exhausts the gases from the chambers A, A', and A². The fresh supply of liquid then enters the chamber A and the operation just described is repeated. The 70 operation in the first series is repeated in the second series in substantially the same manner, the valve mechanism e being similar to the valve mechanism E, the valve mechanism e' being similar to the valve mechanism E', and valves b and b' being similar to the valves B and B', the pipe connections operating in substantially the same way.

For economical operation of the apparatus it is desirable that the lift from the high-pressure chambers should be as great as the gas-pressure will effect, because the chamber will be filled with gas at this pressure in any event. The lift of the low-pressure cylinders will have to be somewhat less in order that the expansive force of the gas may expel the liquid from them. Thus if the lift between the chambers A and A' is one hundred feet the lift between the chambers A' and A² should be fifty feet, because the gas-pressure after expanding to fill both chambers A and A' from an original volume equal to the capacity of the chamber A will be just one-half its original pressure. Then again the lift from the chamber A² to the chamber a should be two-thirds what the lift is from the chamber A' to the chamber A², because the pressure of gas having expanded from the original volume equal to the capacity of the chambers A and A' to a volume one-half greater will be reduced one-third. The lift between the high-pressure chamber a and a' should preferably, of course, be the same as the lift between the chamber A and A'.

The operation hereinbefore described would be complete and effective if the connecting-pipes of the system were filled with liquid before the operation commenced, so that there would be no clearance or other disturbing elements to be taken into consideration. It will readily be seen, however, that in the initial operation of the apparatus the liquid contained in the chamber A will not fill the chamber A', together with the connection formed by the pipe C. The liquid will therefore be entirely expelled from the chamber A before the chamber A' is filled. The float operating in the chamber A' therefore will not have closed the valve E' when the valve E opens

the connection between the chamber A and the chamber A', so that the gas from the chamber A passes directly through the chamber A', the valve E', the pipe F', and valve E' out the exhaust. This permits of a sufficient reduction in pressure in the chamber A to admit of a fresh supply of liquid through the valve B. When the chamber A is again filled, the liquid actuates through the float the valve E and closes the connection through the pipe F and opens the connection with the gas-supply, so that a second chamber full of liquid is expelled from the chamber A through the pipe C into the chamber A'. Now if the chamber A' is filled before the chamber A is emptied in order to allow the complete emptying of the chamber A with a corresponding exact filling of the chamber A' an overflow-valve G' is arranged, through which the surplus liquid forced into the chamber A' may pass. Check-valves B³, B⁴, B⁵, b³, and b⁴ are provided in the liquid-connecting pipes C C' C² and c c' to prevent a return flow of liquid from said pipes. By this arrangement it will readily be seen that after the initial operation just described the liquid expelled from the chamber A will exactly fill the chamber A' with each operation and without overflow, as the chambers are of the same size and the connecting-passages remain filled throughout the operation. An overflow-valve G² operates on the chamber A² in substantially the same way as the overflow G' operates on the chamber A'.

In the passage of the liquid from the chamber A² to the chamber a the same difficulty may be experienced in starting the apparatus as might be experienced between the chambers A and A'—that is, the passage formed by the pipe C² taking from the supply of liquid expelled from the chamber A² may prevent the complete filling of the chamber a, and consequently there would be no operation in the chamber a until a second volume of liquid from the chamber A² was forced into the chamber a. As soon as the valve-chamber a is filled with water the valve e is opened, allowing the actuating-gas to enter into the chamber, and subjects the liquid therein to this pressure, so that of course no further movement of the liquid from the chamber A² would be effected until the entire series above the chamber a were emptied, so as to form an exhaust for the gas in said chamber, and thus permit the remaining liquid in the chamber A² to be lifted in the chamber a. During all this time the apparatus comprising the lower series of chambers would be idle. To obviate this, I have arranged the valve H' with the pipe H², connecting it with the chamber A², and a pipe h, connecting it with the chamber a. The valve H' is arranged to be operated by pressure exerted through the pipe h, so that as soon as the pressure incident to the motor-gas is exerted through the pipe h the valve H' is immediately opened, and this allows the water

which is still subjected to gas-pressure in the chamber A² to pass out through the pipe H². In this manner the entire apparatus may be put into working operation and work continuously thereafter without the active operation either of the valves G', G², g', or H'; but if there is any discrepancy or leakage, so as to prevent the continued operation when this disturbance has sufficiently accumulated after a sufficient number of operations to prevent the continued normal operation of the device, it is corrected by these means, as described.

I have provided a preferable valve mechanism for accomplishing the purposes of the valve mechanism E and e, which may be described as follows: A valve-dome I is arranged on the tops of the high-pressure chambers. A valve-casing I' is secured in said dome by passing the fittings D³ and F³ through the top of the dome and screwing them into the valve-casings I', as shown in Fig. 2. The valve-fitting D³ connects with the pipe D and the fitting F³ connects with the pipe F. The fitting D³ enters a supply-chamber i, and the fitting F³ extends from an exhaust-chamber i'. Between these chambers is a cylinder i², and at one side of the cylinder i² is a valve-motor-valve-chamber i³. The valve J is placed in the supply-chamber i and is formed, much as ordinary check-valves are, with a spider j extending through the opening in the bottom of said chamber. A stud j' extends from the spider j through a cross-head L, to which it is secured by a nut j². The exhaust-valve K is fitted in an opening in the lower part of the exhaust-chamber i' and is provided with the spider k, which forms the guide for the valve, and the stud k', which passes through the cross-head L and to which it is secured by a nut k². The valve J is closed by a movement of the cross-head L in a downward direction, and the valve K is opened by the same movement. On the other hand, the valve J is opened by an upward movement of the cross-head, while the valve K is closed by the same movement. To the center of the cross-head is attached a piston-rod m, which passes through a stuffing-box i⁴ into the cylinder i² and is secured to the piston M, which is placed in said cylinder. A port i⁵ leads from the upper end of the cylinder i² into the valve-chest i³, and a port i⁶ leads from the lower end of said cylinder into said chest. A port i⁷ leads from the upper end of the supply-chamber i into the upper part of the valve-chest i³, and a port i⁸ leads from the central part of said chest into the exhaust-chamber i'. A valve N is arranged in the valve-chest and is of the piston-valve variety, having the enlarged ends n n, which make a close fit, by means of the usual rings, with the walls of the valve-chest. It has also the valve-passage n' between said enlargements and a central opening n² extending from end to end. At the lower end of said valve is a spider, to which is secured a valve-rod N'. The top of

the valve-chest i^3 is provided with a cap i^{11} , through which leads a tube i^{10} . A lubricant may be introduced through the tube i^{10} . The lower end of the chest i^3 is closed by the head 5 i^2 . This head forms a guide for the stem N' . The general operation of this part of the mechanism is as follows: The liquid entering the chamber A operates through a float upon the valve N and raises it, so that the valve- 10 passage n' is brought over the port i^5 and the lower end of the valve is above the port i^6 . Compressed gas entering from the supply-chamber i through the passage i^7 passes through the passage n^2 in the center of the 15 valve through the port i^6 below the piston M, and as the piston M is of greater area than the valve J it immediately lifts the valve J from its seat and closes the valve K. The valve N remains in this position until it is 20 reversed by the action of the float reaching the bottom of the chamber, so that compressed gas is allowed to pass through the supply i into the chamber A until all the liquid in the chamber A is expelled. The action of the 25 float then reverses the valve N, bringing the valve-passage n' over the port i^6 and the top of the valve below the port i^5 . Compressed gas then passes from the chest i^3 into the upper end of the cylinder i^2 and immediately 30 forces the piston M down. This closes the valve J and opens the valve K, thus closing the connection to the fresh gas-supply and opening the connection between the chamber A and the chamber A'.

35 The float mechanism is as follows: Secured to the valve-rod N' is a yoke O, and to this yoke O is secured a float-rod Q. This float-rod has a shoulder or nut q at its lower end, and the yoke O forms a shoulder at the upper end. The float R has a central opening r , through which the rod Q passes, so that the float in its movement slides on the rod Q. The yoke O has an opening or slot o through it, in which is arranged a rounded end p^2 of 40 an arm p' , which is pivoted at p , and has a counterweight P at its opposite end. The counterweight is intended to be of sufficient heft to slightly overcome by its weight the weight of the valve N, yoke O, and rod Q 45 and connected parts when tilted by the action of the float on the yoke O; but it is not so heavy but that the weight of the float R when it reaches the bottom of the chamber upon the shoulder q will draw the valve down, 50 raising the weight P to its upright position. The weight P is not of sufficient weight or at least is not so arranged in relation to the pivot p to move the valve except when given the initial movement by the float R. It will 55 readily be seen that the action of the float upon the shoulder q at one end and the yoke O at the other end, together with the weighted arm, will give to the valve the operation just hereinabove described.

60 65 The valve E', and with it the valves E^2 and e' , may be described as follows: A dome S is secured to the upper end of the tank A'. In

this is the threaded opening F^4 , into which leads the pipe F. The opening F^4 is at all times in communication with the chamber A'. 70 The valve-case T is secured to the dome by passing a threaded portion through an opening in the top of the dome and screwing it into the valve-case T', arranged within the dome. The valve-case is closed at its upper 75 end by a cover T^2 , which screws down on the upper end of the case, and provided with the opening F^5 , which leads into the pipe F'. The valve-case is provided at its lower end with a valve-seat t . The valve U is arranged in the cage T' and has a face adapted to fit on the seat t . Extending upwardly from the valve, through the opening in the valve-seat, is a cylindrical extension u , at the upper end of which is secured a plunger U'. An opening 80 u' is arranged in the upper end of this plunger, which is adapted to be opened and closed by a valve U³. The valve U³ is provided with a ribbed stem U², which extends through the cylindrical extension u , ending in a shoulder 85 u^3 at the lower end. Extending downwardly from the valve is a cage U⁴, having a bottom u^5 screwed therein, and tensioned against this bottom and the shoulder u^3 is a spring u^4 . Openings u^2 are provided in the cage U⁴, 90 which allow a passage of gas by the ribbed stem U² through the cylindrical or sleeve-like extension u , by the valve U³, through the opening u' into the chamber above the plunger U'. A float-rod U⁵ is secured to the stem 95 U² and extends to the bottom of the chamber A'. It is provided at its lower end with a nut U⁶ and at its upper end with a shoulder U⁷. A float V is arranged to slide on the rod U⁵. The spring u^4 is of just sufficient strength 100 to overcome the weight of the rod U⁵ and the stem U² and to seat the valve U³. The area of the plunger U' is considerably larger than the area of the valve U. The operation of this valve is as follows: Starting with the 110 chamber A' empty, the float V will rest on the shoulder U⁶, and the valve U, being free from the action of the pressure, will be drawn off its seat by the weight of the float V acting through the spring u^4 . As the chamber fills 115 with liquid the gas displaced by the liquid passes up by the valve U out of the opening F⁵ into the next chamber or through the exhaust. When the float V is carried up against the shoulder U⁷ by the incoming liquid, it 120 carries with it the valve U and seats it on the seat t . This should occur just previous to the operation of the valve mechanism E, so that the incoming gas from the lower chamber through the opening F⁴ is not allowed to escape by the valve U. As the expansion of the gas from the chamber A expels the liquid from the chamber A' its pressure on the valve U holds it to its seat. When the liquid has 125 reached the bottom chamber A', the float, acting on the shoulder U⁶, overcomes the spring u^4 , and the valve U³, being of but small area, is readily unseated by the weight of the float. 130 This allows the gas under pressure to pass up

through the sleeve-like extension u and opening u' into the chamber above the plunger U' , and this gas being of a pressure equal to that below the valve U the pressure of the gas upon the plunger U' , it being of larger area, immediately opens the valve U and allows the gas to pass up through said valve and out of the opening F^5 into the pipe F .

The overflow-valve G' (also G^2 and g') is as follows: It is provided at the top and bottom with openings F^6 and F^7 , to which the connections are made with the pipe F . Within the valve-chamber G^4 is placed a plunger X , which is of such size as to close but readily slide in the upper part of the case G' . Suspended from the plunger X is a cage X' , on which is a valve x . The valve x covers the opening g^4 and fits on a seat g^5 . It is provided with guides x' , which extend through the opening g^4 . The cage X' is open to the chamber G' , and within this cage is placed a float X^2 . An opening x^2 is arranged in the upper side of the plunger X , and the float X^2 is provided with a valve-surface x^3 on its upper end, which is adapted to seat against the plunger X to close the opening x^2 . When the water rises in the chamber above the level of the float X^2 , it is immediately raised by the liquid, so as to close the opening x^2 . The plunger X is then subjected to the pressure of the liquid, whatever that may be, and this immediately lifts the valve x from its seat, thus allowing the excess of liquid to escape through the opening g^4 . As soon as the gas under pressure is admitted through the pipe F and opening F^6 the float X^2 is pressed off its seat and the plunger X falls to its place and is seated by the pressure.

The drain-valve mechanism H' comprises a case H , having an opening H^3 , to which is connected a pipe H^2 , and an opening h' , to which is connected a pipe h . A plunger or plug W is placed in the upper end of the chamber and subjected to the force of the spring W^3 . A stem w extends downwardly from this plunger and is provided at its lower end with a nut w' , against which is arranged a washer w^2 . A fibrous washer w^3 is secured in place by this washer w^2 and a plate w^4 . A nut w^5 on the end of the stem w holds all these parts in place and forms a valve W' , which is pressed by the spring W^3 against the seat w^6 . An opening W^2 passes through the lower end of the chamber H and is closed by this valve W' . A spring is arranged against the plunger W and is of sufficient strength to hold the valve W' closed against the head in the pipe h , but is not of sufficient strength to withstand the pressure incident to the original gas-supply to which the liquid in the chamber a is subjected, so that while the chamber a is being emptied the valve W' is held open, allowing any surplus which remains in the chamber A^2 to drain off. As soon as the chamber a is emptied and the pressure of the gas therein lessened by expansion sufficient to fill the chamber a' this

pressure is sufficiently reduced to permit the spring W^3 to close the valve W' . By this arrangement the opening and closing of the drain-valve is so timed that no waste takes place except when required to correct the operation of the apparatus.

It will readily be understood that this apparatus may be used for forcing liquids on the level, and in that case the lift would be the friction of the liquid upon the walls of the passages through which it was forced. The operation would be substantially the same, except that there would be greater waste through the length of the gas connecting-pipes, as F . I do not wish to be understood, therefore, to limit myself to an arrangement of chambers one above the other by the use of the term "lift."

In the broader phases of my invention it is not necessary that the lift from the initial chamber, as A , should be expelled into the succeeding chamber, as A' ; but, on the other hand, the operation of the chambers A and A' may be in a measure independent of each other.

I do not claim, broadly, in this application the opening of a connection between the two pump-chambers during a closure of the connection of the source of motor-fluid supply, as this in its broadest form is comprised in the claims of the copending application, Serial No. 666,729, filed January 14, 1898, for "Apparatus for actuating fluid under pressure." Neither do I claim, broadly, the combination of a chamber, means for admitting fluid to be actuated to said chamber, means for conducting the fluid actuated from said chamber, a valve-motor, a valve-chest, a connection between said valve-motor and said chest, a connection between said chest and said chamber independent of the connection between the valve-motor and the chest, and a connection between said chest and a source of motor-fluid supply, and valve mechanism contained in said chest and arranged to control the movement of motor fluid to said chamber and to the valve-motor, as this is comprised in my other application, Serial No. 666,729; nor, in an apparatus for actuating fluid under pressure, the combination of a pump-chamber, a valve-motor, a valve-chest, connections between said valve-chest and the pump-chamber, the valve-motor, and a source of motor-fluid supply, of a main valve arranged to be actuated by said valve-motor and to control the movement of motor fluid to the pump-chamber, and an auxiliary valve contained in said chest for actuating the valve-motor, as this is comprised in my application Serial No. 666,729.

What I claim as new is—

1. In an apparatus for actuating liquid with compressed gas, the combination of two pump-chambers arranged to bring the liquid to be actuated and the actuating-gas into contact within said chambers; a connection leading from one of said chambers to a source

6 of gas-supply; an independent gas connection between said chambers; means for admitting a liquid to each of said chambers; means for conducting an actuated liquid from 5 said chambers; and automatically-actuated valve mechanism for controlling the movement of compressed gas, arranged to open the connection to the gas-supply during a closure of the connection between said chambers, and to govern the connection between said chambers so as to maintain an opening 10 between them during a closure of the connection to the source of gas-supply, and during the emptying of the liquid from the second of 15 said chambers.

2. In an apparatus for actuating liquids with compressed gases, the combination of two pump-chambers arranged to bring liquid 20 to be actuated and actuating-gas into contact within said chambers; a connection leading from the first of said chambers to a source of gas-supply; an independent gas connection between said chambers; a liquid connection between said chambers; means for admitting 25 liquid to the first of said chambers; means for conducting the actuated liquid from the second of said chambers; and automatically-actuated valve mechanism controlling the movement of gas arranged to open the connection 30 to the gas-supply during the closure of the gas connection between said chambers and to govern the connection between said chambers so as to maintain an opening between them during a closure of the connection 35 to the source of gas-supply and during the emptying of the second of said chambers.

3. In an apparatus for actuating liquid with compressed gas, the combination of two pump-chambers of the same size arranged to bring 40 the liquid to be actuated and the actuating-gas into contact within said chambers; a connection leading from one of said chambers to a source of motor-gas supply; an independent gas connection between said chambers; 45 means for admitting a liquid to each of said chambers; means for conducting an actuated liquid from said chambers; and automatically-actuated valve mechanism controlling the movement of compressed gas, arranged to 50 open the connection to the gas-supply during a closure between said chambers, and to govern the connection between said chambers so as to maintain an opening between them during a closure of the connection to the source 55 of gas-supply, and during the emptying of the liquid from the second of said chambers.

4. In an apparatus for actuating liquids by compressed gas, the combination of a high-pressure chamber and a low-pressure chamber 60 arranged to bring the actuating-gas and the liquid to be actuated into contact within said chambers; a connection leading from the high-pressure chamber to a source of gas-supply; means for conducting a liquid to be actuated to each of said chambers; lifts arranged for each of said chambers and proportioned to permit the expulsion of liquid 65

from the low-pressure chamber by the expansive force of the volume of gas in the high-pressure chamber; an independent gas 70 connection between said chambers; and automatically-actuated valve mechanism arranged to open the connection to the gas-supply during a closure of the connection between said chambers to expel the liquid from the high-pressure chamber, and to open the connection between said chambers during a closure of the connection to the gas-supply to allow the expulsion of liquid from the low-pressure chamber by the expansion of gas 80 from the high-pressure chamber.

5. In an apparatus for actuating liquid by compressed gas, the combination of a high-pressure chamber and a low-pressure chamber arranged to bring the actuating-gas and 85 the liquid to be actuated into contact within said chambers; a connection leading from the high-pressure chamber to a source of gas-supply; means for conducting the liquid to be actuated to said high-pressure chamber; an independent gas connection between said chambers; a liquid connection between said chambers; a lift arranged from the low-pressure chamber and in such proportion to the lift incident to the connection between the 90 high-pressure and low-pressure chambers as to permit of the expulsion of the liquid from the low-pressure chamber by the expansion of the gas in the high-pressure chamber; and automatically-actuated valve mechanism arranged to open the connection to the gas-supply during a closure of the gas connection between said chambers to expel the liquid from the high-pressure chamber and to open the gas connection between said chambers 95 during a closure of the connection to the gas-supply to allow the expulsion of the liquid from the low-pressure chamber by the expansion of the gas from the high-pressure chamber. 100

6. In an apparatus for actuating liquid by compressed gas, the combination of a high-pressure chamber and a low-pressure chamber each of the same size arranged to bring the actuating-gas and the liquid to be actuated into contact within said chambers; a connection leading from the high-pressure chamber to a source of gas-supply; means for conducting the liquid to be actuated to said high-pressure chamber; an independent gas 115 connection between said chambers; a liquid connection between said chambers; a lift arranged from the low-pressure chamber and in such proportion to the lift incident to the connection between the high-pressure and low-pressure chambers as to permit of the 120 expulsion of the liquid from the low-pressure chamber by the expansion of the gas in the high-pressure chamber; and automatically-actuated valve mechanism arranged to open the connection to the gas-supply during a closure of the gas connection between said chambers to expel the liquid from the high-pressure chamber and to open the gas connection 125 between the high-pressure and low-pressure chambers. 130

nection between said chambers during a closure of the connection to the gas-supply to allow the expulsion of the liquid from the low-pressure chamber by the expansion of the gas from the high-pressure chamber.

7. In an apparatus for actuating liquid by compressed gas, the combination of a high-pressure chamber, a low-pressure chamber, and a second high-pressure chamber arranged to bring the actuating-gas and liquid to be actuated into contact within said chambers; a connection leading from the high-pressure chambers to a source of gas-supply; means for conducting the liquid to be actuated to said high-pressure chamber; a liquid connection leading from the first high-pressure chamber to the low-pressure chamber; a liquid connection leading from the low-pressure chamber to the second high-pressure chamber; an independent gas connection between the first high-pressure chamber and the low-pressure chamber; an automatically-actuated valve mechanism arranged to open the connection of the first high-pressure chamber to the gas-supply during a closure of the connection between the first high-pressure chamber and the low-pressure chamber, and to govern the connection between said chambers so as to maintain an opening between them during a closure of the connection between the first high-pressure chamber and the source of gas-supply, and during the emptying of the liquid from the low-pressure chamber.

8. In an apparatus for actuating liquid by compressed gas, the combination of a high-pressure chamber, a low-pressure chamber, and a second high-pressure chamber arranged to bring the actuating-gas and liquid to be actuated into contact within said chambers; a connection leading from the high-pressure chambers to a source of gas-supply; means for conducting the liquid to be actuated to the first of said high-pressure chambers; a liquid connection leading from the first high-pressure chamber to the low-pressure chamber; a liquid connection leading from the low-pressure chamber to the second high-pressure chamber, the lift from the low-pressure chamber to the second high-pressure chamber being so proportioned to the lift between the first high-pressure chamber and the low-pressure chamber as to admit of the actuation of the liquid from the low-pressure chamber by the expansion of the gas from the high-pressure chamber; an independent gas connection between the first high-pressure chamber and the low-pressure chamber; and an automatically-actuated valve mechanism arranged to open the connection of the first high-pressure chamber to the gas-supply during a closure of the connection between the first high-pressure chamber and the low-pressure chamber, and to govern the connection between said chambers so as to maintain an opening between them during a closure of the connection between the first high-pressure chamber and the source of gas-supply and during the

emptying of the liquid from the low-pressure chamber.

9. In an apparatus for actuating liquids with compressed gases, the combination of two pump-chambers arranged to bring liquid to be actuated and the actuating-gas into contact within said chambers; a liquid connection between said chambers; a valve mechanism for controlling the actuating-gas; and an overflow-valve for allowing the escape of the liquid in excess of filling the second of said chambers from the liquid expelled from the first of said chambers.

10. In an apparatus for actuating liquids with compressed gas, the combination of two pump-chambers, said chambers being of equal size and arranged to bring liquid to be actuated and the actuating-gas into contact within said chambers; a liquid connection between said chambers; a valve mechanism for controlling the actuating-gas; and an overflow-valve for allowing the escape of the liquid in excess of filling the second of said chambers from the liquid expelled from the first of said chambers.

11. In an apparatus for actuating liquids with compressed gas, the combination of two pump-chambers arranged to bring the liquid to be actuated and the actuating-gas into contact within said chambers; a liquid connection for conveying liquid from the first of said chambers to the second of said chambers; a valve mechanism for controlling the actuating-gas arranged to be actuated by the movement of the liquid in the first of said chambers; and an overflow-valve for allowing the escape of liquid in excess of filling the second of said chambers from the liquid expelled from the first of said chambers.

12. In an apparatus for actuating liquids with compressed gas, the combination of two pump-chambers arranged to bring the liquid to be actuated and the actuating-gas into contact within said chambers; a liquid connection between said chambers; a valve mechanism for controlling the actuating-gas; and an automatically-actuated overflow-valve for allowing the escape of the liquid in excess of filling the second of said chambers from the liquid expelled from the first of said chambers.

13. In an apparatus for actuating liquid with compressed gas, the combination of a high and a low pressure pump-chamber, arranged to bring the liquid to be actuated and the actuating-gas into contact within said chambers; a liquid connection between said chambers arranged to convey a liquid from the high-pressure chamber to the low-pressure chamber; a gas connection between said chambers; a valve for controlling the movement of the actuating-gas; and an automatically-actuated overflow-valve for allowing the escape of liquid in excess of filling the second of said chambers from the liquid expelled from the first of said chambers.

14. In an apparatus for actuating liquid

with compressed gas, the combination of a high and a low pressure pump-chamber, each arranged to bring the liquid to be actuated and the actuating-gas into contact within said chamber; a liquid connection between said chambers arranged to convey a liquid from the high-pressure chamber to the low-pressure chamber; a gas connection between said chambers; a valve device for controlling the actuating-gas to effect the expulsion of the liquid from the high-pressure chamber by the direct pressure of the actuating-gas and the expulsion of the liquid from the second chamber by the expansion of the gas from the first chamber to the second chamber, said valve device being arranged to be actuated by the movement of the liquid in the first of said chambers; and an automatically-actuated overflow-valve mechanism for allowing the escape of liquid in excess of filling the second of said chambers from the liquid expelled from the first of said chambers.

15. In an apparatus for actuating liquids by compressed gas, the combination of two pump-chambers arranged to bring the liquid to be actuated and the actuating-gas into contact within said chambers; a liquid connection between said chambers arranged to convey liquid from the first of said chambers to the second of said chambers; a gas-exhaust valve from the first of said chambers actuated by the movement of the liquid in said chamber; a gas-supply valve on the second of said chambers actuated by the movement of the liquid in said chamber; a normally-closed drain-valve for the first of said chambers; and means actuated with the incoming of actuating-gas in the second of said chambers for opening said drain-valve.

40. 16. In an apparatus for actuating liquids with compressed gas, the combination of a first high-pressure chamber, a low-pressure chamber and a second high-pressure chamber; a liquid connection between the low-pressure chamber and the second high-pressure chamber; a gas connection between the gas-supply and the two high-pressure chambers; a gas connection between the first high-pressure chamber and the low-pressure chamber; a gas-exhaust valve in the low-pressure chamber arranged to be actuated by the movement of the liquid in said chamber; a valve mechanism controlling the supply of gas in the second high-pressure chamber, said valve mechanism being arranged to be actuated by the movement of the liquid in said chamber; a normally-closed drain-valve for the low-pressure chamber; and means actuated with the incoming of actuating-gas in the second high-pressure chamber for opening said drain-valve.

65. 17. In an apparatus for actuating liquids with compressed gas, the combination of a first high-pressure chamber, a low-pressure chamber and a second high-pressure chamber; a liquid connection between the low-pressure chamber and the second high-pressure chamber;

ber; a gas connection between the gas-supply and the two high-pressure chambers; a gas connection between the first high-pressure chamber and the low-pressure chamber; a gas-exhaust valve in the low-pressure chamber arranged to be actuated by the movement of the liquid in said chamber; a valve mechanism controlling the supply of gas in the second high-pressure chamber, said valve mechanism being arranged to be actuated by the movement of the liquid in said chamber; a normally-closed drain-valve for the low-pressure chamber; means actuated with the incoming of actuating-gas in the second high-pressure chamber for opening said drain-valve; and an overflow-valve for allowing the escape of liquid in excess of filling the low-pressure chamber from the liquid expelled from the first high-pressure chamber.

18. In an apparatus for actuating liquids with compressed gas, the combination of a first high-pressure chamber, a low-pressure chamber and a second high-pressure chamber; a liquid connection between the low-pressure chamber and the second high-pressure chamber; a gas connection between the gas-supply and the two high-pressure chambers; a gas connection between the first high-pressure chamber and the low-pressure chamber; a gas-exhaust valve in the low-pressure chamber arranged to be actuated by the movement of the liquid in said chamber; a valve mechanism controlling the supply of gas in the second high-pressure chamber, said valve mechanism being arranged to be actuated by the movement of the liquid in said chamber; a normally-closed drain-valve for the low-pressure chamber; means actuated with the incoming of actuating-gas in the second high-pressure chamber for opening said drain-valve; an overflow-valve for allowing the escape of liquid in excess of filling the low-pressure chamber from the liquid expelled from the first high-pressure chamber; and a valve mechanism for controlling the flow of gas to the first high-pressure chamber and from the first high-pressure chamber to the low-pressure chamber, said valve mechanism being actuated by the movement of the liquid in said first high-pressure chamber.

19. In an apparatus for actuating liquids with compressed gas, the combination of two pump-chambers arranged to bring the liquid to be actuated and the actuating-gas into contact within said chambers; a connection leading from one of said chambers to the gas-supply; an independent gas connection between said chambers; means for admitting the liquid to be actuated to each of said chambers; means for conducting the actuated liquid from said chambers; and an automatically-actuated valve mechanism actuated by a movement of the liquid for controlling the movement of gas arranged to open the connection to the gas-supply during a closure of the connection between said chambers, and to open the connection between said chambers.

bers during a closure of the connection to the source of gas-supply.

20. In an apparatus for actuating liquid with compressed gas, the combination of a high-pressure and a low-pressure pump-chamber, each arranged to bring the liquid to be actuated and the actuating-gas into contact within said chamber; a connection leading from the high-pressure chamber to the source of gas-supply; an independent gas connection between said chambers; means for conducting a liquid to be actuated to each of said chambers; a valve mechanism automatically actuated by the movement of the liquid for controlling the movement of gas arranged to open the connection to the gas-supply during a closure of the connection between said chambers, and to govern said connection between said chambers so as to maintain an opening between them during a closure of the connection to the source of gas-supply and during the emptying of the liquid from the low-pressure chamber.

21. In an apparatus for actuating liquids with compressed gas, the combination of two pump-chambers arranged to bring the liquid to be actuated and the actuating-gas into contact within said chambers; a connection leading from the first of said chambers to a source of gas-supply; an independent gas connection between said chambers; a liquid connection between said chambers; means for admitting liquid to the first of said chambers; means for conducting the actuated liquid from the second of said chambers; a valve mechanism automatically actuated by the movement of said liquid for controlling the movement of gas arranged to open the connection to the gas-supply during a closure of the gas connection between said chambers and to govern the gas connection between said chambers so as to maintain an opening between them during a closure of the connection to the source of gas-supply and during the emptying of the second of said chambers.

22. In an apparatus for actuating liquids by compressed gas, the combination of a high-pressure chamber and a low-pressure chamber each arranged to bring the actuating-gas and the liquid to be actuated into contact within said chamber; a connection leading from the high-pressure chamber to a source of gas-supply; means for conducting the liquid to be actuated to each of said chambers; lifts arranged for each of said chambers in proportion to permit the expulsion of liquid from the low-pressure chamber by the expansive force of the volume of gas in the high-pressure chamber; an independent gas connection between said chambers; a valve mechanism automatically actuated by the movement of liquid arranged to open the connection to the gas-supply during a closure of a connection between said chambers to expel the liquid from the high-pressure chamber, and to open the connection between said

chambers during a closure of the connection to the gas-supply to allow the expulsion of liquid from the low-pressure chamber by the expansion of the gas from the high-pressure chamber.

23. In an apparatus for actuating liquid under pressure the combination of two pump-chambers arranged to bring the liquid to be actuated and the actuating-gas into contact within said chambers; a connection leading from one of said chambers to a source of gas-supply; an independent gas connection between said chambers; means for admitting a liquid to each of said chambers; means for conducting actuated liquid from said chambers; automatically-actuated valve mechanism for controlling the movement of compressed gas arranged to open the connection to the gas-supply during a closure of the connection between said chambers and to govern the connection between said chambers so as to maintain an opening between them during a closure of the connection to the source of gas-supply and during the emptying of the liquid from the second of said chambers, and to exhaust the gas from said chambers after the emptying of the second of said chambers.

24. In an apparatus for actuating liquid under pressure the combination of two pump-chambers arranged to bring the liquid to be actuated and the actuating-gas into contact within said chambers; a connection leading from one of said chambers to a source of gas-supply; an independent gas connection between said chambers; means for admitting a liquid to each of said chambers; means for conducting actuated liquid from said chambers; automatically-actuated valve mechanism for controlling the movement of compressed gas arranged to open the connection to the gas-supply during a closure of the connection between said chambers and to govern the connection between said chambers so as to maintain an opening between them during a closure of the connection to the source of gas-supply and during the emptying of the liquid from the second of said chambers, and to exhaust the gas from said chambers after the emptying of the second of said chambers.

25. In an apparatus for actuating liquid with compressed gas, the combination of two pump-chambers arranged to bring the liquid to be actuated and the actuating-gas into contact within said chambers; a connection leading from one of said chambers to a source of gas-supply; an independent gas connection between said chambers; means for admitting liquid to each of said chambers; means for conducting the actuated liquid from said chambers; valve mechanism automatically actuated by the movement of the liquid from the first of said chambers controlling the movement of compressed gas arranged to open

the connection to the gas-supply during a closure of the connection between said chambers and to govern the connection between said chambers so as to maintain an opening 5 between them during a closure of the connection to the source of gas-supply, and during the emptying of the liquid from the second of said chambers; and an exhaust-valve actuated by the movement of the liquid in the 10 second of said chambers and arranged to exhaust the gas from said chambers after the emptying of the liquid from the second of said chambers.

26. In an apparatus for actuating liquid 15 with compressed gas, the combination of two pump-chambers arranged to bring the liquid to be actuated and the actuating-gas into contact within said chambers; a connection leading from one of said chambers to a source of 20 gas-supply; an independent gas connection between said chambers; means for admitting the liquid to the first of said chambers when the compressed gas is exhausted from said chambers; valve mechanism automatically 25 actuated by the movement of liquid in the first of said chambers for controlling the movement of compressed gas arranged to open the connection to the gas-supply when said pump has become filled with liquid, and during a 30 closure of the connection between said chambers and to govern the connection between said chambers so as to maintain an opening between them after the emptying of said first chamber during a closure of the connection 35 to the source of gas-supply and during the emptying of the liquid from the second of said chambers; and an exhaust-valve actuated by the movement of the liquid in the second of said chambers to exhaust the compressed gas 40 from said chamber after the emptying of the liquid from said second chamber.

27. In an apparatus for actuating liquid with compressed gases, the combination of the pump-chambers, A and A'; the check-valves, B and B', leading to said pump-chamber; liquid connection, C, leading from the chamber, A, to the chamber, A'; a check-valve, B³, therein; a supply connection, D; the gas connection, F, between the chambers, 45 A and A'; the valve mechanism, E, arranged to control the flow of gas to and from the chamber, A; a float for actuating said valve mechanism to open the connection between said chamber, A, and the supply-pipe, D, during a closure of the connection through the pipe, F, and to open a connection through the pipe, F, during a closure of the connection through the pipe, D.

28. In an apparatus for actuating liquid 60 with compressed gases, the combination of the pump-chambers, A and A'; the check-valves, B and B', leading to said pump-chambers; liquid connection, C, leading from the chamber, A, to the chamber, A'; a check-valve, B³, therein; a supply connection, D; the gas connection, F, between the chambers, 65 A and A'; the valve mechanism, E, arranged

to control the flow of gas to and from the chamber, A; a float for actuating said valve mechanism to open the connection between 70 said chamber, A, and the supply-pipe, D, during a closure of the connection through the pipe, F, and to open a connection through the pipe, F, during a closure of the connection through the pipe, D; valve mechanism, E', 75 on the chamber, A'; and a float for actuating said valve to exhaust the gas in said chamber after the emptying of said chamber of liquid.

29. In an apparatus for actuating liquid with compressed gas, the combination of the 80 pump-chambers, A and A'; the check-valves B and B', leading to said pump-chamber; liquid connection, C, leading from the chamber, A, to the chamber, A'; a check-valve B³, therein; a supply connection, D; the gas connection, F, between the chambers, A and A'; the valve mechanism, E, arranged to control the flow of gas to and from the chamber, A; a float for actuating said valve mechanism to open the connection between 85 said chamber, A, and the supply-pipe, D, during a closure of the connection through the pipe, F, and to open a connection through the pipe, F, during a closure of the connection through the pipe, D; and an overflow-valve, G', for 90 automatically permitting the escape of any excess from the filling of the chamber, A, by a liquid expelled from the chamber, A.

30. In a valve device for controlling gases in an apparatus for actuating liquids with 100 compressed gas, the combination of the valve-case, I', containing the supply-chamber, i, having the supply-passage therefrom, an exhaust-chamber, i', having an exhaust-passage thereto, a cylinder, i², a valve-motor valve-chest, i³, a port, i⁷, leading from the supply-chamber to the valve-chest, a port leading from the valve-chest to the exhaust-chamber, and ports, i⁵ and i⁶, leading from the cylinder, i², to said valve-chest; the valve, J, controlling the passage from the supply-chamber; the valve, K, controlling the passage to the exhaust-chamber; the piston, M, arranged in the cylinder, i²; the piston-rod, m, extending from said piston; the cross-head, L, secured to the valves, J and K, and rod, m; a valve in said valve-chest for controlling the movement of the gases to and from the ports, i⁵ and i⁶; and means for actuating said valve.

31. In an apparatus for actuating liquids with compressed gas, the combination of a chamber arranged to bring the liquid to be actuated and the actuating-gas into contact within said chamber; the valve-case, I', containing the supply-chamber, i, having the supply-passage therefrom, an exhaust-chamber, i', having an exhaust-passage thereto, a cylinder, i², a valve-motor valve-chest, i³, a port, i⁷, leading from the supply-chamber to 115 the valve-chest, a port leading from the valve-chest to the exhaust-chamber, and ports, i⁵ and i⁶, leading from the cylinder, i², to said valve-chest; the valve, J, controlling the pas- 120

sage from the supply-chamber; the valve, K, controlling the passage to the exhaust-chamber; the piston, M, arranged in the cylinder, i^2 ; the piston-rod, m, extending from said piston; the cross-head, L, secured to the valves, J and K, and rod, m; a valve in said valve-chest for controlling the movement of the gas to and from the ports, i^3 and i^6 ; means for actuating said valve; and a float actuated 10 by the movement of the liquid in said chamber for actuating said valve.

32. In an exhaust-valve mechanism for an apparatus for actuating fluids by compressed gas, the combination of a case having a passage through it, and the valve-seat thereon; a plunger arranged to operate within said case; a valve connected within said plunger and actuated thereby from its seat; an auxiliary valve connecting the gas-supply with 20 the valve-case outside of said plunger, said auxiliary valve having a smaller area than the exhaust-valve; and a float arranged to actuate said valve.

33. In an exhaust-valve mechanism for an apparatus for actuating liquids by compressed gas, the combination of the case, T, having a passage therethrough and a valve-seat thereon; the opening, F^5 , therein; the plunger, U', arranged in said case; the valve, 25 U, operating upon the seat on said case; a sleeve-like extension, u, connecting the plunger, U', with the valve, U; an auxiliary valve, U ^{3} , operating upon an opening in the plunger; a stem extending from said valve through 35 the sleeve, u; means for normally keeping the valve, U ^{3} , to its seat; a float-rod connected with said stem; and a float arranged on said stem.

34. In an exhaust-valve mechanism for an apparatus for actuating liquid by compressed gas, the combination of the case, T, having a passage therethrough upon which is a valve-seat, t, and an opening, F^5 ; the plunger, U', in said case of larger area than the seat, t, 40 and having an opening, u', therein; the valve, U, operating upon the seat, t; the sleeve, u, connecting the valve, U, with the plunger, U'; an auxiliary valve, U ^{3} , operating upon the opening, u'; means for normally pressing 45 said valve to its seat; means for limiting the outward movement of the valve, U; a float-rod connected to the stem of the auxiliary valve; and a float arranged to actuate said rod.

35. In an exhaust-valve for an apparatus 55 for actuating liquids by compressed gas, the combination of the fitting, S, having the opening, F^4 , therein; the valve-case, T, passed through said fitting, said case having the passage through it around which is a valve-seat, t, and also an opening, F^5 , therethrough; a cage T', within the fitting, S, for securing the case in place; the plunger, U', arranged 60 within the case and having an opening, u', therein, said plunger being of greater area than the passage by the seat, t; the valve, U, arranged in the cage, T', adapted to be seated 65 on the seat, t; the sleeve, u, connecting the

plunger U', with the valve, U; the auxiliary valve, U ^{3} , arranged over the opening, u'; the valve-stem, U ^{2} , extending from the auxiliary 70 valve through the sleeve, u; the cage, U ^{4} ; the shoulder, u ^{5} , on the stem, U ^{2} ; and the spring, u ^{6} , tensioned against said shoulder; the float-rod, U ^{5} , connecting with the stem, U ^{2} ; and the float, D, arranged to operate said rod. 75

36. In an apparatus for actuating liquids by compressed gas, the combination with the chamber arranged to bring the actuating-gas and the liquid to be actuated into contact within said chamber; an overflow-valve connected with said chamber comprising a case, 80 passages to said case for a gas-supply, and a valve in said case actuated to allow the escape of liquid from said chamber when said liquid exceeds a certain amount, and to be 85 closed by the gas-pressure when admitted to said chamber.

37. In an apparatus for actuating liquids by compressed gas, the combination with the chamber arranged to bring the actuating-gas 90 and the liquid to be actuated into contact within said chamber; an overflow-valve connected with said chamber comprising a case having a passage therethrough for the gas-supply, a float-actuated valve therein ar- 95 ranged to be opened by the liquid, and to be closed by the gas-pressure.

38. In an apparatus for actuating liquid by compressed gas, the combination with the chamber arranged to bring the actuating-gas 100 and the liquid to be actuated into contact within said chamber; an overflow-valve connected with said chamber comprising a case, a plunger in said case having an opening therethrough, a float arranged to close said 105 opening in said plunger, and a valve actuated by said plunger for opening and closing an opening in said case to allow the outflow of excess of liquid.

39. In an apparatus for actuating liquid by 110 compressed gas, the combination with the chamber arranged to bring the actuating-gas and liquid to be actuated into contact within 115 said chamber; an overflow-valve connected with said chamber comprising the case G ^{4} , having the plunger, X, therein, with the opening, x ^{2} , therethrough, the cage, X', carried by said plunger and having the valve, x, thereon, and the float, X ^{2} , having the valve-surface, x ^{3} , thereon arranged within said cage. 120

40. In an apparatus for actuating liquid by compressed gas, the combination with the chamber arranged to bring the actuating-gas and the liquid to be actuated into contact within said chamber; an overflow-valve connected with said chamber comprising the case, G ^{4} , having the openings, F ^{6} , F ^{7} , and g ^{4} , therein, the plunger, X, arranged within said case having the opening, x ^{2} , therein, the cage, X', suspended from said plunger and carrying 130 the valve, x, thereon, arranged to operate over the opening, g ^{4} , and the float, X ^{2} , within said cage having the valve-surface, x ^{3} , thereon, adapted to close the opening, x ^{2} .

41. In an apparatus for actuating liquid by compressed gas, the combination of the chambers, A^2 and a ; the valve-case, H ; the plunger-valve, W , arranged within said case; the spring W^3 , tensioned against said plunger; the valve, W' , actuated by said plunger; the pipe, h , connecting the plunger end of said case; and the pipe, H^2 , connected with said gas below said plunger and above the valve, W' .
42. In an apparatus for actuating liquid by compressed gas, the combination of the chamber, A , the chamber, A^2 , and the chamber, a ; a liquid connection between the chamber, A , and the chamber, A^2 ; a gas connection between the chamber, A , and the chamber, A^2 ; checks in the liquid connections for preventing the return flow of the liquid; a liquid

connection between the chamber, A^2 , and the chamber, a ; a connection between the chambers, A and a , and the gas-supply; valve mechanism, E and e , on the chambers, A and a , respectively, said valve mechanism being arranged to be actuated by a float in said chambers; a drain-valve H' , connected with the chamber, A^2 ; the pipe, h , connecting said valve with the chamber, a ; and pipe, H^2 , connecting said valve with the chamber, A^2 , for the purposes described.

In testimony whereof I affix my signature in presence of two witnesses.

RUDOLPH CONRADER.
